CLAIM

We claim the ornamental design for a garbage receptacle, as shown and described.

DESCRIPTION

FIG. 1 is a perspective front view of the garbage receptacle embodying my new ornamental design;

FIG. 2 is a perspective rear view of the garbage receptacle;

FIG. 3 is a bottom plan view thereof;

FIG. 4 is a side elevational view thereof, the sides other than those shown in FIG. 4 being identical thereto; and,

FIG. 5 is a top plan view thereof.
